TRANSPORTING TANK

William R. Kepler, Wauwatosa, and Eric H. Nilson, Milwaukee, Wis., assignors to A. O. Smith Corporation, Milwaukee, Wis., a corporation of New York

Application December 10, 1937, Serial No. 179,051

2 Claims. (Cl. 105—362)

This invention relates to an improvement in transporting tanks or containers and provides a simple and inexpensive means of fastening the tank to railroad flat cars or motor vehicle carriers. The invention is particularly well adapted to the transportation of cylindrical storage tanks of the type illustrated in U. S. Patent #2,092,165 issued on September 7, 1937 to William R. Kepler for Support for cylindrical vessels, wherein the tank is supported at four points at its outer extremities.

It is an object of the present invention to provide means for supporting a tank, when loaded on a freight car, which will permit movement relative to the carrying platform to the extent necessary to prevent deformation from sudden shocks such as occur during transportation.

A further object is to provide a number of tieing means which will independently resist forces that may arise in various directions or affect different parts of the tank.

Another object is to utilize the supporting structure of the tank as a terminus for tie rods to prevent fore and aft movement relative to the carrier and to cushion the attachment thereto in such a manner as to prevent injury to the tank.

These and other objects, which will be more particularly described herein, are accomplished by the embodiment illustrated in the accompanying drawing, in which:

Fig. 1 is a side view showing a tank mounted on a railroad flat car;

Fig. 2 is an end view of the tank and car shown on Fig. 1;

Fig. 3 is a detail of the attachment of the tie rods to the supporting fins of the tank and to the car.

The tanks illustrated are frequently of a length in excess of 40 feet and a diameter in excess of 11 feet and accordingly can be placed as a unit on a flat car of customary dimensions. Smaller tanks may be placed on trucks or a series of such tanks loaded on flat cars without departing from the scope of this invention.

The tank 1, as illustrated, is supported at four points by the fin plates 2 welded to the tank head at the ends of the cylindrical section. Stiffening plates 3, seat plates 4, and bracket plates 5 attached to the fin plates 2 complete the supporting structure and are similar to elements illustrated in the Kep'ler patent heretofore mentioned.

Each support rests on a block or blocks 6, which may conveniently be made of wood. The blocks must be thick enough to provide clearance between the bottom of the tank and the

floor of the car. A metal plate 7 is welded onto a larger plate 8 and disposed at right angles to the fin plate 2 for supporting the latter, the plate 8 being nailed to block 6 and the upper surface of plate 7 being preferably greased to allow for easy longitudinal movement of the plate 2 therewith. The plates 7 and 8 are positioned to engage the inside edge of the seat plates 4 so as to hold the tank rigidly against lateral movement relative to the car.

Spaced longitudinally along the tank are a series of bands 9 drawn tightly over the top of the tank and fastened to the frame of the flat car by tie rods 10, tie rod plates 11, and nuts 12. Most flat cars are provided with stake holders 13, 15 through which the tie rods may be drawn, but if none are provided, holes may be drilled in the car floor and the rods inserted through them. The number of bands required will depend in part upon the length of the tank. For most tanks 20 three bands are sufficient, one at each end, spaced a short distance from the heads and holding the tank firmly on the blocks 6, and one in the central portion. Occasionally it may be necessary to have two bands in the central area. The use of 25 bands instead of one continuous rod is preferable because of the greater contacting area covered by bands. Any suitable connection may be used to fasten the bands to the rod, a weld 14 being illustrated on the drawing.

The middle of the tank is supported by four blocks 15 with top surfaces shaped to conform to the contour of the tank which rests upon them. A felt lining 16 is placed between the tank shell and the blocks to cushion the tank from sudden 35 shocks. Such protection is more important where enamel lined tanks are being transported.

To hold the tank against longitudinal movement on the car, each of the four supports is resiliently connected to the car by a tieing member. The tie rod 17 is drawn through an opening in the fin plate 2 and extends diagonally downward toward the opposite end of the tank, its lower inner end being secured to the car. Abutting against the fin plate and enclosing the tie 45 rod at its upper end outside the fin plate 2 is a pipe section 18. Washers 19 spaced by a compressible rubber block 20 are held in place by a nut 21 which is tightened to equal tension on all of the tie rods.

The tie rods 17 are preferably drawn as nearly horizontal as possible and attached to the car at a point considerably remote from the end supports. By making the attachment to the fin plates near the vessel shell, the rods may be drawn 55

under the bracket plates 5 and the vertical bands 9 without causing any interference with the functioning of these parts. The attachment to the car may be made similar to that for the vertical bands, as has already been described.

The tie rod 17 between the fin plate 2 and the car is preferably formed of three parts, the central section being a bar 22, connecting two threaded end tie rods 21' and 23. The attachment 10 may be conveniently made by welding as at 24 and 25. In this construction, the tie rod 23, attached to the car frame, may consist only of a vertical rod, bar 22 being bent to lie parallel thereto for welding, and a bent plate 26 inserted 15 through the stake holder serving as a support.

The construction of the tie rods, having the rubber blocks 20 allows a limited longitudinal movement of the tanks on plates 7 responsive to severe forward and backward movement of the 20 car and therefore relieves the fin plates 2 of severe stress from shocks. The tanks are fully protected against injury from shocks.

The invention having been described what is claimed is:

25 1. In combination with a transporting car a large cylindrical tank having a pair of braced lateral supporting fins immovably secured thereto at each head, longitudinally extending blocks on the platform of the car for supporting said 30 fins, means passing over the top of the tank for

securing the same down on said blocks, means on the fins for engaging the blocks to prevent relative lateral movement between the tank and the car, a pair of longitudinally extending tie rods on each side of the tank each rod having one end secured to the car and the other end resiliently engaging a supporting fin to permit limited relative longitudinal movement between the tank and car.

2. In combination with a transporting car a large cylindrical tank having a pair of braced lateral supporting fins immovably secured thereto at each head, longitudinally extending blocks on the platform of the car for supporting said fins, means passing over the top of the tank for securing the same down on said blocks, means on the fins for engaging the blocks to prevent relative lateral movement between the tank and the car, a pair of longitudinally extending tie rods on each side of the tank, the rods in each pair having their adjacent inner ends secured to the car and their outer ends slidably projecting through their respective fins, cushioning means interposed between the fin and an adjustable abutment on the outer end of each rod to permit 25 limited relative longitudinal movement between the tank and car.
